S. C. MARKATOS

ATTACHMENT FOR HOT WATER BOILERS

Filed Sept. 26, 1925

UNITED STATES PATENT OFFICE.

SPIROS C. MARKATOS, OF NEW YORK, N. Y.

ATTACHMENT FOR HOT-WATER BOILERS.

Application filed September 26, 1925. Serial No. 58,892.

This invention appertains to novel means for associating a hot plate with the upper end of a hot water or steam boiler such as is utilized in hat blocking, steaming and pressing machines whereby the heat from the boiler as well as the heat arising from the heating means of the boiler can be utilized for maintaining the plate in a hot condition, the position of the plate relative to the boiler also conserving space; and is an improvement over my Patent 1,497,730 issued to me June 17, 1924.

The primary object of the present invention is to provide novel means for connecting the said stove or hot plate with the upper end of the steam or hot water boiler which is of an exceptionally simple and durable character and which will permit the stove to be readily associated with the boiler in a minimum amount of time and positively hold the stove rigidly on the boiler against accidental displacement.

A further object of the invention is the provision of novel clamps carried by the legs of the hot plate or stove for gripping contact with the rivets utilized for connecting the conventional head of the boiler with the shell thereof, whereby movement of the hot plate or stove relative to the boiler will be entirely eliminated.

A still further object of the invention is to provide novel means for connecting an iron holder or hot plate with the conventional steam or hot water boiler of a hat blocking, steaming and pressing machine of the above character, which will be durable and efficient in use, one that will be simple and easy to manufacture and one which can be placed upon the market at a reasonable cost without necessitating any change to the iron holder or hot plate and the boiler.

With these and other objects in view, the invention consists in the novel construction, arrangement and formation of parts as will be hereinafter more specifically described, claimed, and illustrated in the accompanying drawings, in which drawings;

Figure 1 is a side elevation showing the iron holder plate secured, in accordance with this invention, to the top of a conventional type of hot or steam boiler.

Figure 2 is a horizontal section taken on the line 2—2 of Figure 1 looking in the direction of the arrows, and

Figure 3 is a detail perspective view of one of the novel clamping members.

Referring to the drawings in detail, wherein similar reference characters designate corresponding parts throughout the several views, the letter A indicates the iron holder or hot plate, B the hot water or steam boiler and C the novel means for associating the iron support or hot plate with the said boiler.

The iron support or hot plate A is of the conventional type and includes the usual body 5 and the depending supporting legs 6. Disposed in the body 5 is the usual gas burner 7 which is supported in any desired way.

The hot water or steam boiler B is also of the conventional type utilized in hat blocking, cleaning and pressing machines and embodies the usual shell 10, and head 11 connected by rivets 12.

The novel means C for connecting the iron support or hot plate A with the boiler B embodies clamps or brackets 15 for each leg 6 of the said iron support or hot plate.

In order to economize on space and to effectively heat the said iron holder or hot plate from the boiler and the heating means of the boiler, the said iron holder or hot plate is arranged directly above the upper end of the boiler, so that the heat arising therefrom will effectively keep the iron holder or hot plate in a warm condition, thus effectively saving on the gas generally consumed for heating the said iron holder or hot plate.

Each of the clamps or brackets 15 include an upper straight body or attaching portion 16 and a lower depending hook shaped portion 17. The body or attaching portions 16 are adapted to be placed in abutting relation with the lower ends of the legs 6 of the iron holder or hot plate A, while the arcuate or hooked shaped portions 17 are placed in engagement with the upper end of the boiler B in gripping contact with the rivets 12. Suitable machine screws or the like are extended through openings in the straight body or attaching portion 16 of the clamp and threaded into the sockets or the like formed in the legs 6 of the iron holder or hot plate.

In placing the iron holder or hot plate on top of the boiler the clamps 15 are loosely attached to the legs 6 and the iron holder or hot plate is placed in position. The arcuate or clamping portions 17 are placed over the heads of adjacent rivets and the screws

18 are tightened so as to force the clamps in gripping contact with the heads of the rivets.

This will hold the iron holder or hot plate firmly in position and owing to the shape of the arcuate or clamping jaw portions and engagement thereof with the rivets movement of the iron holder or hot plate relative to the boiler is prevented and the accidental displacement of said iron holder or hot plate from off of the boiler is entirely eliminated.

From the foregoing description, it can be seen that I have provided novel and exceptionally simple and durable means for connecting an iron holder or hot plate to the upper end of a boiler.

Changes in details may be made without departing from the spirit or the scope of this invention, but:

20 What I claim as new is:

1. The combination with a boiler of the class described and an iron holder arranged directly above the boiler including depending legs, the boiler including the usual body shell and head and rivets connecting the head with the shell, of means for firmly connecting the iron holder with the boiler embodying depending adjustable clamps carried by the legs of the iron holder, each of the clamping members including arcuate gripping jaws for snugly receiving the heads of the rivets.

2. The combination with a boiler of the class described embodying a shell and a head and rivets connecting the head with the shell and an iron holder arranged in superimposed relation to the boiler including depending legs, of means for firmly connecting the iron holder with the boiler embodying clamping members carried by the legs, each of the clamping members including a straight attaching portion for engaging the legs and a depending arcuate jaw portion for snugly receiving the adjacent rivet heads of the boiler, and adjustable means connecting the straight body portions of the clamps to the legs for moving the jaw portions into and out of contact with the rivet heads.

3. The combination with an iron supporting plate and a boiler provided with out-

wardly extending rivet heads adjacent the top thereof, of a plurality of brackets provided with means operatively engaging the said rivet heads to prevent disengagement of the brackets therefrom while the same are contacting with the boiler, and means for securing said brackets to the said supporting plate, the last-mentioned means causing the brackets to clamp against the outer wall of the said boiler and to engage the said rivet heads.

4. The combination with an iron supporting plate and a boiler provided with outwardly extending rivet heads, of a plurality of brackets provided with recesses for operatively engaging the rivet heads to prevent disengagement of the brackets therefrom while the same are contacting with the boiler, and means for securing the said brackets to said iron supporting plate, said means clamping the brackets against the outer wall of the said boiler, and the said recesses in engagement with the said rivet heads.

5. In combination with a boiler having exposed projecting rivet heads, a hot plate, and clamps carried by the plate and enclosing and embracing certain of said rivet heads for attaching said plate to the boiler.

6. In combination with a boiler having projecting rivet heads, a hot plate, and clamps removably secured to the hot plate for movement into and out of embracing engagement with certain of said rivet heads.

7. In combination with a boiler having a series of projecting rivet heads, a hot plate, supports for spacing said plate a predetermined distance above the top of the boiler to accommodate thereunder a burner, and individually removable clamps embracing certain of said rivet heads for attaching the hot plate to the boiler.

8. In combination with a water boiler having exposed projecting rivet heads, a hot plate structure arranged at the top of the boiler, and having an engageable detachable connection with certain of said rivet heads.

In testimony whereof I affix my signature.

SPIROS C. MARKATOS.
